UNITED STATES PATENT OFFICE.

FRED BRYANT, OF MATTEAWAN, NEW YORK.

SILK-THROWSTER SPINDLE.

No. 884,126.

Specification of Letters Patent.

Patented April 7, 1908.

Application filed June 3, 1907. Serial No. 377,016.

To all whom it may concern:

Be it known that I, FRED BRYANT, a citizen of the United States, residing at Matteawan, in the county of Dutchess and State of New York, have invented certain new and useful Improvements in Silk-Throwster Spindles, of which the following is a specification.

This invention has for its object a simple, durable and efficient construction of silk throwster spindle, which will effectually hold the bobbin thereon and at the same time prevent it from turning relatively to the spindle as the latter is rotated, and the invention consists in certain constructions and arrangements of the parts that I shall hereinafter fully describe and claim.

For a full understanding of the invention and the merits thereof and also to acquire a knowledge of the details of construction of the means for effecting the result, reference is to be had to the following description and accompanying drawings, in which

Figure 1 is a longitudinal sectional view of my improved spindle with the bobbin thereon. Fig. 2 is a detail perspective view of the spindle detached.

Corresponding and like parts are referred to in the following description and indicated in all the views of the drawings by the same reference characters.

My improved silk throwster spindle is provided with the usual journal ends and is also provided at one end with the usual cylindrical head 2. A tapered bushing 3 surrounds one end of the spindle 1 and fits within the inner side of the head 2, said bushing tapering towards the opposite end of the spindle, as clearly illustrated in the drawings. Preferably this bushing is secured to the spindle by the same pin 4 which secures the head 2 thereon.

5 designates a bobbin which may be of any desired shape or construction, except that its socket or bore which receives the spindle is tapered at one end as indicated at 6, the tapered bushing 3 being adapted to wedge snugly in such tapered end of the bore.

The spindle 1 is hollow, as shown, and it contains a spring latch bar 7 which is provided at one end with an offset lug 8 adapted to fit into a small aperture in the spindle to hold the latch bar secure in place. The latch bar 7 is also formed in advance of the lug 8, with a bearing lug or protuberance 9, adapted to bear against the wall of the spindle and serving as a fulcrum point when the

latch bar is flexed, or held under tension at its opposite end 10. The said latch bar is provided with a relatively broad shoulder 11 and a bulged or rounded head 11^a beyond said shoulder, the said end 10 normally springing outwardly, when permitted to do so, through the longitudinal slot 12 in the spindle. The proportions of the parts are such that when the bobbin is slipped over the spindle with the tapered bushing 3 fitting snugly in the tapered end of the bore of the bobbin, the shoulder 11 will engage with the opposite end of the bore in the bobbin, while the bulged or rounded head 11^a will protrude from that end of the bobbin and bear against the said end so as to hold the bobbin snugly on the spindle, the spring latch bar 7 being held under tension and the head 11^a effectually preventing the bobbin from working longitudinally off the spindle. The shoulder 11 bears outwardly against the bobbin at one end of the bore, and the tapered bushing edges into the tapered portion of the bore. Hence, any rotary movement of the bobbin independently of the spindle is effectively prevented.

Having thus described the invention, what is claimed as new is:

1. As a new article of manufacture, a spindle of the character described, provided near one end with a tapered bushing designed to fit in the bore of a bobbin and provided near its other end with a longitudinal slot, and a spring latch bar contained within the spindle and secured thereto at one end, said latch bar being provided at its other end with a shoulder and a bulged head beyond the shoulder, said shoulder and head normally springing out through the slot and adapted to engage the end of the bobbin bore and the end of the bobbin respectively.

2. As a new article of manufacture, the herein described spindle, provided near one end with a longitudinal slot, and a spring latch bar mounted within the spindle and secured thereto at one end, said latch bar being provided intermediate of its ends with a protuberance bearing against the spindle and serving as a fulcrum for the latch bar, and said latch bar being provided at its other end with a shoulder and a head beyond and projecting above the shoulder.

3. The combination of a bobbin, provided with a spindle bore which is tapered at one end, a spindle provided near one end with a tapered bushing adapted to fit in the tapered

2
end of the bore and provided at its other end with a longitudinal slot, a spring latch bar mounted within the spindle and secured thereto at one end, said latch bar being provided intermediate of its ends with a protuberance adapted to bear against the spindle and constituting a fulcrum for the latch bar, said latch bar being provided at its opposite end with a shoulder and a bulged head beyond the shoulder, the shoulder and head being adapted to protrude through the said slot, with the shoulder bearing against the bobbin at one end of the bore and the head bearing against the extreme end of the bobbin. ¹⁵
In testimony whereof I affix my signature in presence of two witnesses.

FRED BRYANT. [L. s.]
